UNITED STATES PATENT OFFICE.

ALBERT FRANCIS STONE, JR., OF CALLAHAN, CALIFORNIA.

BOOK-HOLDER.

932,348.

Specification of Letters Patent. Patented Aug. 24, 1909.

Application filed April 23, 1909. Serial No. 491,729.

To all whom it may concern:

Be it known that I, ALBERT FRANCIS STONE, Jr., a citizen of the United States, and a resident of Callahan, in the county of 5 Siskiyou and State of California, have invented a new and Improved Book-Holder, of which the following is a full, clear, and exact description.

The invention is an improved holder for 10 magazines and other books and is designed to hold the book open at the desired point and support the book at each side, the side or cover supports being adjustable to support the book when fully open, hold the book 15 closed, and support the separated portions of the book in intermediate positions.

Reference is to be had to the accompanying drawings forming a part of this specification, in which similar characters of reference 20 indicate corresponding parts in all the views.

Figure 1 is a view of my improved book holder as applied to a magazine, in perspective, the parts of the holder being in position to hold the magazine open; Fig. 2 is a side 25 view of the holder partly in central vertical section, as applied to a magazine, showing the position of the parts of the holder in full lines when the magazine is closed and in dotted outline when in an operative and intermediate position; and Fig. 3 is a fragmentary 30 rear view of the holder in perspective and in cross-section.

The holder as preferably constructed embodies a spring clip or gripping device 5 in 35 the form of a relatively long trough-like member of sheet metal to bind on the bound edge of the magazine or other book, the free edges of the clip being pressed slightly inwardly, as shown in Fig. 3, in order to afford 40 a firm grip on the book along these lines. The corners of the clip are turned outwardly slightly and rounded as indicated at 5^a, to prevent them from engaging the book and tearing the cover when the clip is applied and 45 removed. Seated on the rear or bottom wall within the clip is a tube 6, which extends slightly beyond the clip at each end and at the upper end portion is provided with a close-fitting tubular plug 7, through which 50 passes a sliding rod 8, the latter being bent upon itself into U-form, with the arm of the rod at the outside of the clip of substantial length, with the extremity 9 bent outwardly to prevent it from digging into the book, and 55 the arm of the rod within the tube slightly longer than the other arm and provided with

a head or enlargement 10 at the end, to contact with the inner end of the tubular plug 7 and prevent the further outward movement of the rod when moved to the outer dotted 60 position shown in Fig. 2. The plug 7 is of wood or such other material that will afford the proper frictional contact with the rod, and while admitting of it being easily slid back and forth with the hand yet prevents it from 65 sliding until intentionally moved.

A wing 11 to support each side of the book is preferably constructed of wire, with the ends of the wire wound about the extended end portions of the tube 6 to form hinges, and 70 with the extremities of the wire bent cross-wise of the windings or coils and longitudinally of the tube, as indicated at 12. These portions 12 of the wire on opposite wings contact when the wings are fully opened, as 75 shown in Fig. 3, and prevent the further movement of the wings outwardly.

In the application and use of the holder, the clip 5 is passed endwise over the bound edge of the book and brought to a substantially central position, the rod 8 at this time being in the position shown in Fig. 2, and the wings slightly separated to admit of the book easily passing between them. In reading the book or magazine, the latter is separated 80 at the point desired, moving the wings 11 outwardly on their hinges. The rod 8 is then withdrawn from the tube to the outer dotted position shown in Fig. 2, after which it is reversed or revolved one hundred and eighty 85 degrees and forced downwardly or inwardly between the leaves of the book at the point selected, as shown in the lower dotted position of Fig. 2 and in full lines in Fig. 1. In this position of the rod the two portions of 90 the book are pressed to the wings and the book may be conveniently held with one hand by grasping the clip 5, which serves as a handle. The hinges of the wings on the end portions of the tube are sufficiently stiff 95 to hold the wings in any position in which the latter are set, as well as to hold the book closed when the parts of the holder are in the position shown in full lines in Fig. 2.

Having thus described my invention, I 100 claim as new and desire to secure by Letters Patent:

1. In a book holder, a clip to bind on the bound edge of the book at the outside, and a member to engage in the angle between the 105 leaves of the book and hold the book open, slidably carried on the clip.

2. In a book holder, a clip to bind on the bound edge of the book at the outside, wings to support the book at opposite sides, carried by and movable to and from each other, and a member movably supported on the clip to engage between the leaves of the book and force the separate portions of the book to the wings.
3. In a book holder, a clip to bind on the bound edge of the book, wings to support the book at opposite sides, carried by the clip and movable to and from each other, and a member to engage between the leaves of the book and force the separated portions of the book to the wings, slidably supported in the clip.
4. In a book holder, a clip to bind on the bound edge of the book, and a member having two approximately parallel arms, with one of the arms slidably supported within the clip and the other arm movable therewith and adapted to pass between the leaves of the book to hold the book open.
5. In a book holder, a clip movable edge-wise over the bound edge of the book, a tube within the clip and extending therebeyond at each end, wings to support the book at

opposite sides, hinged to the extended end portions of the tube, and a U-shaped rod, with one of the arms of the rod slidably supported in the tube and the other arm of the rod arranged at the outside of the clip to engage between the leaves of the book and force the separated portions thereof to the wings.

6. In a book holder, a clip to bind on the bound edge of the book, having extensions at the ends, wire wings to support the book at opposite sides, with the ends of the wire of each wing wound about the extensions to form hinges and having the extremities turned crosswise of the windings to form a stop in connection with the ends of the wire of the opposite wing to limit the separation of the wings.

In testimony whereof I have signed my name to this specification in the presence of two subscribing witnesses.
